Inventor.

UNITED STATES PATENT OFFICE.

GEORGE C. WORTMAN, OF DENVER, COLORADO.

COMBINED RAIL-BRACE AND SPIKE-HOLDER.

1,323,802.

Specification of Letters Patent.

Patented Dec. 2, 1919.

Application filed October 4, 1918. Serial No. 256,804.

To all whom it may concern:

Be it known that I, GEORGE C. WORTMAN, a citizen of the United States, residing at the city and county of Denver and State of Colorado, have invented certain new and useful Improvements in Combined Rail-Brace and Spike-Holders; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to a rail brace and spike holder for use in connection with railroad rails, my object being to provide a thoroughly practical device of this character, which shall at the same time be simple in construction and economical in cost. In my improvement, no exposed fastening devices are employed. The spikes which hold the rail in place have their heads engaged from above so that the spikes cannot work loose. Heretofore, so far as I am aware, great difficulty has been experienced by reason of the spikes becoming loose and working upwardly out of the ties, thus leaving the rail loose and liable to spread when in use.

Another object of my improvement is to overcome this difficulty by the employment of a construction which is secured in place without the aid of fastening devices which are liable to become loose.

Generally speaking, my improvement consists of a base plate, having an inwardly turned flange adapted to engage the heads of the spikes on one side of the base of the rail, the spikes being first driven into the tie through elongated openings in the plate, after which the plate is moved laterally with reference to the rail, or longitudinally of the tie, until the inwardly bent flange engages the spike heads. On the opposite side of the rail I employ a brace member which engages the upper surface of the said plate and when in place also engages the spikes on the adjacent side of the rail and further extends upwardly into engagement with the ball of the rail at the angle between it and the web. This brace is held in place on the plate by means of a key, of wedge or other

shape, adapted to securely hold the brace in 55 position.

Having briefly outlined my improvement, I will proceed to describe the same in detail, reference being made to the accompanying drawing, in which is illustrated an embodiment thereof. In this drawing:

Figure 1 is a vertical cross section taken on the line 1—1, Fig. 2, showing my improved construction in use.

Fig. 2 is a fragmentary side elevation of 65 a rail and tie, shown in connection with my improvement.

Fig. 3 is a fragmentary, perspective view of a tie and rail, showing my improvement applied.

Fig. 4 is a perspective view of the plate, or bottom member of my improvement.

Fig. 5 is a perspective view of the rail brace member thereof.

Fig. 6 is a similar view of a locking key 75 employed, and forming a part of the device.

Fig. 7 is a cross section, illustrating the first step in applying my improvement to a rail.

Fig. 8 is a section taken on the line 8—8, 80 Fig. 4, looking toward the left.

The same reference characters indicate the same parts in all the views.

Let the numeral 5 designate a railway rail of ordinary construction. This rail, where 85 my improvement is applied, rests upon a plate, 6, which is provided near one edge thereof with elongated openings, 7, adapted to receive spikes, 8. Adjacent these openings, 7, the edge of the plate is bent inwardly above the openings 7 to form a spike-holding flange, 9, the plate being shifted laterally under the base of the rail after the spikes are in place in order to bring the flange over and directly in contact with the 95 spike heads on this side of the rail. The spikes, 8, are driven into the ties through the openings 7, when the plate is shifted sufficiently for the purpose, as best illustrated in Fig. 7.

The plate is further provided with openings, 10, adapted to receive spikes, 12, which are of the same construction as the spikes 8. After the plate, 6, has been shifted to bring the flange, 9, into locking engagement with the spikes, 8, the spikes, 12, are driven into place through the openings, 10, after which a brace, 13, is put in place. This brace is

angular in shape, its outer portion, 14, having a flat lower surface, 15, adapted to engage the upper surface of the plate, 6. It is further provided with a surface part, 16, 5 which is inclined upwardly from the surface 15, and so arranged as to engage the tops of the spikes, 12, in locking relation. The upper portion, 17, of the brace extends upwardly at a suitable angle, its upper edge 10 engaging the rail at the upper extremity of the web, where the ball, 18, joins the web.

The part 14 of the rail brace member cooperates at its outer edge with an upwardly projecting rib, 25, the outer edge of the brace 15 and the inner surface of the rib being spaced to receive a locking key, 26, which may be composed of any suitable material. As shown in the drawing, this key is composed of hard wood, though it is evident that any 20 suitable material may be employed. By making the key of hard wood, it may be driven so tightly into place that there is practically no liability of its becoming loose under the influence of the vibration of the 25 rails while a train is passing.

As shown in the drawing, the plate, 6, is provided with a horizontal flange or part, 27, which extends beyond the rib, 25, and is provided with openings, 28, adapted to receive fastening devices, in the event that an 30 emergency should exist requiring that the plate be fastened otherwise than by means of the construction heretofore described. This extension is not regularly utilized but 35 if for any reason the tie should become defective where the spikes 8 and 12 are located, and it should be sound where the extension 27 is, by placing fastening devices in the openings 28, the rail might be temporarily 40 held sufficiently secure for operating purposes, until the track could be repaired by the substitution of a new tie.

From the foregoing description, the use 45 and operation of my improvement will, it is believed, be thoroughly understood without further explanation in detail.

Attention is called to the fact that it is preferred that the flange, 9, particularly at its extremities, should be bent downwardly, 50 as shown at 30, in order to prevent the flanger or device carried by the locomotive for cutting the ice and snow away from the rails, from catching on the flange, 9, when the so-called flanger is lowered, as it sometimes is, to occupy a position close to the 55 base of the rail. This flanger, or ice- and snow-cutting device, very frequently pulls out the spikes when it is lowered too far. But where my improvement is employed, and 60 the spike-heads are covered by the part 9, this difficulty will be overcome, and by bending the extremities of the flange 9 downwardly, producing a sort of beveled effect, there will be no possibility that the so-called 65 flanger will catch upon the part 9, since it

will move upwardly at the beveled ends, 30, of the flange and slide freely over the latter without injury to either the flange or the adjacent spikes.

Having thus described my invention, what 70 I claim is:

1. A holder for the spikes of railway rails, comprising a base plate, upon which the rail rests, the plate having openings for the spikes, these openings on one side being elongated to permit the shifting of the plate laterally when the spikes are in place, the plate having an inwardly turned flange for engaging the spikes after the shifting of the plate, a second plate arranged above the 75 first plate and adapted to engage the spike heads on the opposite side from the flange, and a locking key, the base plate having a rib, the said key being driven between the outer edge of the second plate and the rib 80 of the base plate.

2. A combined rail brace and spike holder, comprising a base plate upon which the rail rests, the plate having openings for the spikes on opposite sides, the openings on one 85 side being elongated to permit the shifting of the plate laterally when the spikes which engage the elongated openings are in position, the said plate having an inwardly turned flange for engaging the spikes after 90 the shifting of the plate, a second plate arranged above and in contact with the base plate, and adapted to engage the spike heads on the opposite side from the flange, and also to engage and brace the rail, and a locking 95 key, the base plate having a rib, the said key being driven between the outer edge of the second plate and the rib of the base plate.

3. The combination with a rail and tie, 105 of a base plate, arranged between the rail and the tie and having an upturned flange on one edge, the said plate having spike openings on opposite sides and being laterally shiftable after the spikes on one side 110 are in place, one set of openings being elongated for this purpose, a second plate, arranged above the base plate and on the opposite side of the rail from the flange, the second plate engaging the heads of the adjacent spikes from above, and means for 115 securing the second plate in co-operative relation with the base plate and the rails.

4. The combination with a rail and tie, 120 of a base plate, arranged between the rail and the tie and having an upturned flange on one edge, the said plate having spike openings on opposite sides and being laterally shiftable after the spikes on one side are in place, one set of openings being elongated 125 for this purpose, a second plate, arranged above the base plate and on the opposite side of the rail from the flange, the second plate engaging the heads of the adjacent spikes from above, means for securing the second 130

plate in coöperative relation with the base plate and the rail, said means including a rib formed on the base plate, and a locking key arranged between the rib and the second plate.

5. The combination with a rail and tie, of a base plate arranged between the rail and the tie and having an upturned flange on one edge, the base plate having spike 10 openings on opposite sides and being laterally shiftable after the spikes on one side are in place, one set of openings being elongated for this purpose, a second plate arranged above and in contact with the base 15 plate and on the opposite side of the rail from the flange, the second plate engaging the heads of the adjacent spikes from above, and engaging the rail in bracing relation, and means for securing the second plate in 20 coöperative relation with the base plate and the rail.
6. The combination with a rail and tie, of a base plate arranged between the rail and the tie and having an upturned flange on 25 one edge, the base plate having spike open-

ings on opposite sides and being laterally shiftable after the spikes on one side are in place, the openings on the corresponding side being elongated for the purpose, and a brace plate arranged above the base plate and on 30 the opposite side from the flange, the brace plate engaging the heads of the adjacent spikes from above and engaging the rail in bracing relation, and means for securing the brace plate in coöperative relation with 35 the base plate and the rail, said means including a rib formed on the base plate and a locking key driven between the adjacent edge of the brace plate and the rib.

7. The combination with a rail and tie of 40 a base plate, arranged between the rail and the tie and having an upturned flange on one side, the said plate having spike openings on opposite sides and being laterally shiftable after the spikes on one side are in place, 45 the opposite ends of the said flange being bent downwardly to form a bevel or incline for the purpose set forth.

In testimony whereof I affix my signature.
GEORGE C. WORTMAN.
